UNITED STATES PATENT OFFICE

LEONARD DE WIT, OF CHICAGO, ILLINOIS, ASSIGNOR TO MOORE BROTHERS COMPANY,
OF JOLIET, ILLINOIS, A CORPORATION OF ILLINOIS

DESIGN FOR A CIRCULATING HEATER

Application filed April 9, 1931. Serial No. 39,418. Term of patent 3½ years.

To all whom it may concern:

Be it known that I, LEONARD DE WIT, a citizen of the United States, residing at Chicago, county of Cook, and State of Illinois, have invented a new, original, and ornamental Design for a Circulating Heater, of which the following is a specification, reference being had to the accompanying drawings, forming a part thereof:

In the drawings:

Figure 1 is a perspective view of the heater showing my new design;

Fig. 2 is an end view thereof; and
Fig. 3 is a top plan view of the same.
The body is flat at the back as indicated at 4. The front and sides of the stove are arranged in a single substantially semi-circular or semi-cylindrical vertical plane as indicated at 5.

I claim:

The ornamental design for a circulating heater as shown, and described.

LEONARD DE WIT.
